CLAIM

The ornamental design for a protective case for a mobile phone including integral collapsible selfie stick, as shown and described.

DESCRIPTION

FIG. 1 is a perspective view of a protective case for a mobile phone including integral collapsible selfie stick;

FIG. 2 is a front view thereof;

FIG. 3 is a rear view thereof;

FIG. 4 is a right-side view thereof;

FIG. 5 is a left-side thereof;

FIG. 6 is a top view thereof;

FIG. 7 is a bottom view thereof;

FIG. 8 is a front perspective view thereof, showing the integral collapsible selfie stick in an extended configuration;

FIG. 9 is an enlarged detailed view taken from circle 9 in FIG. 1; and,

FIG. 10 is an enlarged detailed view taken from circle 10 in FIG. 8.

The dot-dash broken line circles in FIGS. 9 and 10 are included for the purpose of illustrating the enlarged views and form no part of the claimed design.

The dash-dash broken lines and unshaded regions represent portions of the protective case for a mobile phone including integral collapsible selfie stick that form no part of the claimed design. The interior of the protective case shown in FIG. 3, except for the interior edges of the camera opening, form no part of the claimed design. Similarly, the Bluetooth feature shown in FIGS. 1, 2, and 8-10 form no part of the claimed design.
